UNITED STATES PATENT OFFICE.

ROY W. BROWN, OF AKRON, OHIO, ASSIGNOR TO THE FIRESTONE TIRE AND RUBBER COMPANY, OF AKRON, OHIO, A CORPORATION OF OHIO.

INSTRUMENT PUMP.

Application filed February 20, 1925. Serial No. 10,526.

This invention relates to instrument pumps and particularly devices for maintaining a uniformly constant flow or constant flows of a gas or gases or mixtures thereof through a device such as an indicating or recording instrument. The invention also relates to a method of pumping fluids. A specific application of the pump as will be described herein, is for maintaining flows of gases, one from a chamber containing a mixture of gases and the other from a source of one of the gases of the mixture through an instrument for indicating or recording the percentage of the gases in the mixture. It will be understood, however, that the pump of the invention is capable of general application.

In solvent recovery, such as the recovery of benzol or other solvent from a mixture with air or an inert or other gas, where the solvent is explosive it is often desirable to maintain the mixture in the chamber below a certain percentage of the explosive solvent. In driers such as used for drying fabric or the like which has been coated with rubber by dipping the fabric into a solution of rubber in benzol, the benzol is usually evaporated from the fabric by heaters in an atmosphere of producer gas or carbon dioxide, and in order that the supply of carbon dioxide to the drier can be governed for maintaining a low percentage of solvent in the atmosphere of the chamber, an instrument has heretofore been employed for indicating the percentage of the solvent at all times. This instrument has included a Wheatstone's bridge having resistance elements therein over one of which the mixture of solvent and gas from the chamber is conducted and over the other of which the producer or other gas in the condition in which it is fed into the chamber is conducted, the bridge being so designed and arranged that it is balanced when the percentage of solvent in the mixture does not exceed the safe maximum and a galvanometer will indicate that the percentage of solvent is too high whereupon the valve controlling the supply of carbon dioxide may be operated to remedy the condition.

The present invention has for an object the provision of a pump capable of maintaining a constant flow or constant flows of a gas or gases through an instrument or other device such as described above.

Another object is to provide an improved method for pumping fluids.

A particular object is to provide a pump functioning on the principle of an aspirator or steam injector and arranged to be automatically controlled to draw a gas at a constant velocity through an instrument or the like.

Another object is to provide a pump as described above arranged to maintain a constant head of a liquid therein through which head of liquid the pump will be effective to draw the gas or gases from a chamber or other source through the instrument or the like, the head of liquid being also adapted to provide a telltale or indicator showing that the pump is operating properly, the pump being housed in a transparent container for this latter purpose.

The above and other objects of the invention are obtained by the construction illustrated in the accompanying drawings and described in detail below. It is to be understood that the invention is not limited to the specific construction shown and described.

Of the accompanying drawings:

Figure 1 is a front elevation partly in section of a pump constructed in accordance with the invention;

Figure 2 is a vertical diametrical section on line 2—2 of Figure 1; and

Figure 3 is a plan thereof.

Referring to the drawings, 10 is preferably a transparent casing of glass or other material, having a top 11 of metal or other material secured thereon, the joint between casing 10 and top 11 being sealed to render the casing air-tight as by means of a gasket 12. A bottom 13 of metal or other material is secured onto casing 10 and the joint between casing 10 and the bottom is correspondingly sealed by a gasket 14 rendering the casing 10 air-tight and water-tight. Extending through casing 10 is an aspirator 15 including members 16 and 17, the former being threaded through top 11 and provided with a lateral inlet 18 leading to its bore 19, the upper end of which is closed by a plug 20. The nozzle of member 16 is indicated at 21 and it is encircled by member 17, the bore 17^a of which is internally threaded at its upper end so as to be secured to an externally threaded portion of member 16 above the nozzle 21. The bore 17^a extends through member 17 and is constricted as at 22 adjacent nozzle 20 and gradually becomes larger toward the bottom of member 17. Member 17 extends through bot-

tom 13, the aperture in bottom 13 for this purpose being sealed by a packing 23 urged into a groove 24 about the member 17 in the lower face of bottom 13 by a nut 24^a threaded onto 5 the lower end of aspirator member 17. Above the constricted portion 21 of the bore 17^a and above the nozzle 20 of member 16, the member 17 is apertured as indicated at 25, 25.

Mounted on the top 11 is a valve body 26 10 provided with apertures 27 and 28, respectively, adapted for having connected thereto conductors, one of which leads from a chamber containing mixed gases or the gas and solvent through the instrument for measuring 15 the percentage of gases in the mixture or the percentage of solvent and the other one of which leads from a source of one of the gases through said instrument. Apertures 27 and 28 are respectively, connected by ducts 29 20 and 30 to bores 31 and 32 in valve body 26, bores 31 and 32, respectively, having tubes 33 and 34 connected thereto and arranged to extend downwardly in casing 10 to adjacent bottom 13, the tubes being reversely bent at 25 their bottom portions to provide upwardly directed outlets 35 and 36. Valve body 26 is secured on top 11 by an extension 26^a thereon screw-threadedly received in a threaded aperture 26^b in top 11, bores 31 and 32 being ar- 30 ranged so as to extend through the extension 26^a. For controlling the flow through the pump, valves 37, 38 are respectively arranged to operate in ducts 29 and 30, the valves being formed on stems threaded through apertures 39 and 40 in valve body 26 and operable 35 respectively by knobs 41 and 42. To seal apertures 39 and 40, packings 43 and 44 are respectively provided around valve stems 37 and 38 and are held under compression 40 against valve body 26 by screw caps 45 and 46 threaded thereon.

Arranged below bottom 13 is a pan 47 secured thereon and sealed at the joint with bottom 13 by a gasket 48, the pan 47 being 45 formed with a trough-shaped outlet 49 under which is arranged a suitable drain pipe 50. The drain outlet 49 is of sufficient height above the bottom of pan 47 to maintain a quantity of a liquid therein of such height 50 that the lower end of member 17 will project below the surface thereof and also, so that the liquid will overflow a wall 51 into a compartment 52 in the pan 47 so as to provide a seal for a pipe or tube 53 connected with the interior of casing 10 by being threaded through an aperture 54 in bottom 13.

The pump may be suitably secured as on a wall or the like by means of a bracket 55 suitably secured to the top 11.

60 In the use of the pump, the conductors or pipes through which the flow of gas or gases are to be pumped are connected to ducts 27 and 28. Water or other fluid is then supplied through inlet 18 and as it passes through 65 aspirator 15 it creates a suction through

apertures 25 as will be understood. The water is discharged into pan 47 in which it rises to the level shown, surplus water flowing into drain 50. As soon as the lower end of tube 53 is sealed the suction through apertures 25 70 is effective to draw water from pan 47 up through tube 53 into casing 10 in which it rises to the height of openings 25 and then redischarges through member 17 into the pan. The aspirator maintains this level, the water 75 circulating through member 17, pan 47, tube 53 and casing 10 to the level indicated and then through ducts 25, etc. Surplus water continuously passes out drain outlet 49 into drain 50.

80 The suction created by aspirator 15 under the above described conditions will now tend to evacuate the space in casing 10 above ducts 25 and will draw the mixed solvent and gas and the pure gas through the instrument system through the valves 37 and 38, through the tubes 33 and 34 into the casing 10 against the constant head of water therein, the gases bubbling through the water (Figure 1) into the space thereabove in casing 10 from which 85 they will continuously be exhausted by the aspirator 15. Valves 37 and 38 are adjusted to secure the desired flow and to provide for the same rate of flow of both the mixture of solvent and gas and the pure gas.

90 Due to the constant head of liquid maintained in casing 10 against which the gases are drawn through the pump and due to the fact that variation in the velocity of water through the aspirator will be effective only 100 to vary the rapidity of circulation of the water without varying the suction effective above the level of the water, the velocity at which the gas or gases will be pumped through a system will be uniformly constant. 105

Modifications of the invention may be resorted to without departing from the spirit thereof or the scope of the appended claims.

What is claimed is:

110 1. A constant flow pump comprising a vessel having a fluid inlet therein and means for evacuating the vessel, said evacuating means being adapted to maintain a constant head of a liquid in the vessel above said inlet.

115 2. A constant flow pump comprising a vessel having a fluid inlet therein and means for evacuating the vessel, said evacuating means being adapted to maintain a constant head of a liquid in the vessel above said inlet and adapted to draw a fluid from said inlet 120 through said head of liquid.

125 3. A constant flow pump comprising a vessel having a fluid inlet therein and means for evacuating the vessel, said evacuating means being adapted to maintain a constant head of a liquid in the vessel above said inlet and adapted to draw a fluid from said inlet through said head of liquid, said vessel having a transparent wall.

130 4. A constant flow pump comprising a ves-

sel having a fluid inlet therein, an aspirator in the vessel, means for supplying a liquid to the aspirator, means for discharging the liquid from the aspirator, and means whereby the suction created in the vessel will be effective to fill the chamber to a constant level above said inlet with the liquid discharged from the aspirator.

5. A constant flow pump comprising a vessel, an aspirator extending through the vessel, means for supplying a liquid to the aspirator, means for receiving liquid from the aspirator, said aspirator tending to evacuate the vessel as the liquid passes therethrough, and 10 means extending from the receiving means into the vessel for conducting the liquid thereto, said aspirator being adapted to draw said liquid up from the receiving means to a constant level in the vessel, and means for discharging a fluid from a fluid-conducting system at a point below said level of liquid.

6. A pump for producing uniform flows of gases through a plurality of systems, said pump comprising a vessel having an outlet at 15 the same level therein from each such system, and means for creating a vacuum in said vessel and adapted to provide a constant head of a liquid above said outlets.

7. A pump comprising a closed vessel, an 20 aspirator extending through the vessel and tending to maintain a vacuum therein, means for furnishing a liquid to the aspirator, and means for discharging the liquid from the aspirator, said last means being adapted to provide a supply of liquid to be drawn into the 25 vessel by the aspirator,

8. An instrument pump comprising a closed vessel, an aspirator operable in the vessel, means for supplying a liquid to the aspirator,

said aspirator discharging outside the vessel, 40 and means whereby said aspirator will be effective to draw a portion of the liquid discharged therefrom up into the vessel to a constant level.

9. An instrument pump comprising a closed vessel, an aspirator operable in the vessel, means for supplying a liquid to the aspirator, said aspirator discharging outside the vessel, and means whereby said aspirator will be effective to draw a portion of the liquid discharged therefrom up into the vessel to a constant level, and to recirculate said water with 50 its discharge.

10. An instrument pump comprising a closed vessel, an aspirator extending through the vessel and operable therein, means outside the vessel for supplying a liquid to the aspirator, a pan outside of the vessel for receiving the liquid therefrom, said pan having a discharge outlet therefrom so arranged as to provide for maintaining a quantity of the liquid in said pan, and liquid conducting means connected to the interior of the vessel and extending into the liquid in the pan.

11. An instrument pump comprising a closed vessel having an outlet from a fluid conducting system therein, an aspirator extending through the vessel and operable therein, means for supplying a liquid to the aspirator, a pan for receiving the liquid from the aspirator and adapted to maintain a supply of liquid therein, and a liquid conductor extending into the supply of liquid in the pan and leading into the interior of the vessel whereby said aspirator will be effective to provide a constant head of the liquid in the vessel above said outlet.
